Fig. 1.

Fig. 2.

FIGURE 1 is a perspective view of a laboratory sink table. The side not shown in FIGURE 1 is like the side shown while the back is plain and unornamented; and FIGURE 2 is a side elevational view of the table topped laboratory sink shown in FIGURE 1.

This application is a continuation-in-part of my co-pending application, Ser. No. D. 4,334, filed Oct. 19, 1966, and now abandoned.

I claim:

The ornamental design for a laboratory sink table, substantially as shown and described.
